UNITED STATES PATENT OFFICE.

WILLIAM E. PRICE, OF NEW YORK, N. Y.

DESIGN FOR A REFLECTOR.

Application filed March 3, 1924. Serial No. 8,805. Term of patent 3½ years.

To all whom it may concern:

Be it known that I, WILLIAM E. PRICE, a citizen of the United States, residing at New York, in the county and State of New York, have invented a new and ornamental Design for Reflectors, of which the following is a specification, reference being had to the accompanying drawing, forming a part thereof.

Figure 1 is a side view of the reflector, and

Figure 2 is a bottom plan view.

The device illustrated is designed particularly for use with stage lighting effects and comprises a plurality of reflecting surfaces arranged on a frame in the design shown.

I claim:

The ornamental design for a reflector, as shown.

WILLIAM E. PRICE.
